CLAIM

The ornamental design for a motorcycle, as shown and described.

DESCRIPTION

The patent or application file contains at least one drawing executed in color. Copies of this patent or patent application publication with color drawing(s) will be provided by the Office upon request and payment of the necessary fee.

1. Motorcycle

1.1 is a left side elevation view of a motorcycle showing my new design;

1.2 is a right side elevation view thereof;

1.3 is a front elevation view thereof;

1.4 is a rear elevation view thereof;

1.5 is a top plan view thereof; and

1.6 is a bottom plan view thereof.

1 Claim, 6 Drawing Sheets**(6 of 6 Drawing Sheet(s) Filed in Color)**(56)
